No. 878,692.

PATENTED FEB. 11, 1908.

J. URBANEK.

RAIL JOINT.

APPLICATION FILED MAY 28, 1904.

UNITED STATES PATENT OFFICE.

JOSEPH URBANEK, OF SCHUYLER, NEBRASKA.

RAIL-JOINT.

No. 878,692.

Specification of Letters Patent.

Patented Feb. 11, 1908.

Application filed May 23, 1904. Serial No. 209,355.

To all whom it may concern:

Be it known that I, JOSEPH URBANEK, a citizen of the United States, residing at Schuyler, in the county of Colfax and State of Nebraska, have invented a new and useful Improvement in a Rail-Joint, of which the following is a specification.

This invention relates generally to rail joints and more particularly to one which has for its object to provide a safe and efficient connection between the meeting ends of railroad rails and which will at the same time avoid the jar incidental to the passage of the wheel over the joints now in common use.

Another object of the invention is to provide a rail joint which will provide an unbroken tread without weakening the rails or the means for fastening the meeting ends together.

With these objects in view my invention consists essentially in tapering the tread of the meeting ends of the rails by cutting the head of the rails away at each side so that when the said rails are arranged end to end a V-shaped recess will be arranged at opposite sides of the joint and into which fit the triangular shaped projections carried by the fish plates connecting the meeting ends of the rails, said triangular shaped projections fitting snugly in the V-shaped recesses and completing the tread of the rail at the joint.

The invention consists also in certain details hereinafter fully described and pointed out in the claims.

In the drawings forming a part of this specification: Figure 1 is a perspective view of a complete rail joint constructed in accordance with my invention. Fig. 2 is a view showing in perspective the meeting ends of the rails. Fig. 3 is a view showing in perspective the fish plates employed for uniting the rails. Fig. 4 is a detail perspective view of the base plate or chair.

Referring to the drawings A A indicate the meeting ends of two ordinary railroad rails, the head of the rail being cut away obliquely upon the opposite sides as most clearly shown at A' so that when the rails are arranged end to end as shown in Fig. 1 a wide V-shaped recess A² is produced upon the opposite sides of the head of the rail. It will be noted that the base and web of the rail are not reduced in any manner what-

ever. The ends of the rails rest upon the base plate or chair B which is formed with upwardly and inwardly projecting edges B' notched at B² upon the outer side of the angle to receive the ordinary securing spikes.

C indicate the fish plates arranged upon the opposite sides of the meeting ends of the rails the lower outer edges C' of said fish plates contacting with the upwardly and inwardly extending edges B' of the base plate or chair B. Each fish plate C has an upward extension D arranged centrally of the upper edge said extension D being triangular in horizontal cross-section and of a size and shape to fit snugly in the wide V-shaped recess A². Thus it will be seen that when the parts are assembled the fish plates combine the meeting ends of the rails the same as usual and the triangular shaped extensions fit into the recesses produced upon the opposite sides of the joint and thereby span the joint between the meeting ends of the rails. By having the ends of the rail cut away upon the opposite sides as shown and having the extensions triangular in shape the wheel of the car will roll upon this extension across the joint without any jar whatever whereas if the ends of the rail were cut away on an angular line and the extensions D made with square ends there would be a certain amount of jar incidental to the wheel rolling upon the said extensions.

It will be further noticed that along its lower edge the fish plate C is angled downwardly, as at C², and the edge beveled, and this portion C² fits between the base of the rail A and the flange B' of the chair, the lower, inner portion of the said flange being cut or angled to fit snugly the beveled edge of the angled portion C² of the fish plate, as is shown at B³.

Having thus fully described my invention, what I claim as new and desire to secure by Letters Patent, is:

In a rail joint, the combination with a base-plate having upwardly and inwardly projecting edges provided with notches, of rails arranged on said plate having their heads cut away obliquely upon both sides at their meeting ends forming a V-shaped recess upon opposite sides of the head of the rail, said base plate being of a greater width than the base of the rails, fish-plates arranged upon opposite sides of the meeting ends of the rails, the lower outer ends being

bent downwardly and the edges beveled adapted to fit between the base of the rails and the flanges of the plate, and an upwardly extending extension arranged centrally on 5 the upper edge of the fish-plates, triangular in horizontal cross-section and of a size and shape to fit snugly in the V-shaped recesses,

said fish-plates being secured together by bolts.

JOSEPH URBANEK.
